EX

DESIGN.

S. M. RICHARDSON.
HASP HOOK.

D No. 2,237.

Patented Dec. 26, 1865.

Samuel M. Richardson of New York N. Y.
Letters Patent No. 2387 Dated Decr. 26. 1865
Designs for a Hasp Hook.

The schedule referred to in these Letters Patent and making part of the same.

To all whom it may concern.

Be it known that I, Samuel M. Richardson, of the City and State of New York, have invented or produced a new and original Design for a Hasp hook, and I do hereby declare the following to be a correct description of the same, reference being had to the annexed drawing, making part of this specification, wherein Fig. 1, is an elevation of said hook and hasp, and Fig. 2, is a section at the line X, X.

My invention has reference to the shape and configuration of the T shaped hook or fastening attached to the hasp a, by the rivet b.

The shape of this hook c, will be apparent from the drawing. The body portion 1, is rounded at the junction thereof to the head portion 2, as at 3, 3; and the ends of said head portion 2, are rounded at the parts which enter the staple d, and the back of the head 2, is not flat, but curved as seen in Fig. 2, at the end portions 4, which are contiguous to the hasp plate a.

What I claim and desire to secure by Letters Patent is, the Design of the shape and configuration of the T hook or fastening on the hasp as shown.

In witness whereof I have hereunto my signature this 29th of November 1865.
